IMPULSE SWITCH

Carl Herman Millerwise, Trumbull, Conn., assignor to American Radiator & Standard Sanitary Corporation, New York, N.Y., a corporation of Delaware
Filed Apr. 18, 1960, Ser. No. 22,825
4 Claims. (Cl. 260—77)

This invention relates to an impulse switch, i.e., a switch wherein movement of an actuator is effective to cause a momentary movement of a switch contact to one position, after which said contact is automatically moved to a second position.

One object of the present invention is to provide an impulse switch which is of jam-free construction.

Another object of the invention is to provide an impulse switch wherein the component parts are compactly arranged with respect to one another so as to permit construction of the switch as a small-size item.

Another object of the invention is to provide an impulse switch wherein the component parts are of rugged construction so as to permit manufacture of a switch having a long service life.

Another object of the present invention is to provide an impulse switch wherein the operating parts are accurately guided for slidable reciprocal movement so as to permit jam-free operation.

Another object of the invention is to provide an impulse switch which can employ certain standard switch components, thereby enabling a manufacturer to incorporate an impulse switch in his line of switches without extensive tooling designed especially for the impulse switch.

Another object of the invention is to provide an impulse switch wherein the components can be quickly and easily assembled together by low cost assembly techniques so as to enable manufacture of the switch as a relatively low cost item.

Other objects of this invention will appear in the following description and appended claims, reference being had to the accompanying drawings forming a part of this specification wherein like reference characters designate corresponding parts in the several views.

In the drawings:

FIGURE 1 is a sectional view through one embodiment of the invention, said embodiment being shown with its actuator button 10 in an elevated "de-actuated" position;

FIG. 2 is a sectional view through the FIG. 1 embodiment with actuator button 10 shown in a partially depressed condition;

FIG. 3 is a sectional view through the FIG. 1 embodiment with the actuator button 10 shown in a fully depressed condition; and

FIG. 4 is a sectional view taken substantially on line 4—4 in FIG. 1.

Before explaining the present invention in detail, it is to be understood that the invention is not limited in its application to the details of construction and arrangement of parts illustrated in the accompanying drawings, since the invention is capable of other embodiments and of being practiced or carried out in various ways. Also, it is to be understood that the phraseology or terminology employed herein is for the purpose of description and not of limitation.

In the drawings there is shown an impulse switch structure of the invention constructed to include a casing 12 formed by the dielectric casing elements 14 and 16, and the securing rivets 20 and 22.

Casing structure 12 defines a horizontally elongated switch chamber 24 in which is positioned a metallic support member 26. Support member 26 is upwardly

2

bulged at 28 to define a supporting portion for the central section 30 of a metallic switch blade 32. By reference to FIG. 4 it will be seen that blade 32 is provided with two longitudinal parallel slits 34 and 36 which divide the blade into three separate but connected sections 30, 38 and 40. Sections 38 and 40 are positioned out of vertical registry with the upwardly bulged portion 28 to that said blade sections 38 and 40 may be moved downwardly alongside the lateral edges of portion 28 as shown in FIG. 2. It will be noted that the center blade section 30 is initially deformed downwardly at 42 to position it out of the blade plane defined by blade sections 38 and 40. The preset deformation at 42 is effective to put the blade sections 38 and 40 in tensioned conditions for causing the blade contact structure to normally (FIG. 1) pressingly engage against contact member 46 which is electrically connected with a lead in terminal 45. A second contact member 48 is connected with a lead in terminal 50.

It will be understood that one or both of members 46 and 48 may be connected by means of their terminals into an electric circuit in accordance with the particular installation in which it is desired to locate the switch structure. Current supply for the switch structure is obtained through a terminal 51 formed integrally with metallic support plate 26. Thus, when members 46 and 48 are utilized as current conductors, current flow in the FIG. 1 position is from terminal 51, through support plate 26, switch blade 32, member 46, and its terminal 45. When the switch is in the FIG. 2 position current flow is from terminal 51 to the support plate 26, blade 32, member 48, and its terminal 50. It will be understood that contact members 46 and 48 form stops to limit movement of the blade.

In order to move the switch blade 32 from its FIG. 1 to its FIG. 2 position there is provided a depressable plunger 54 which engages the left end portion of the blade extending above the upwardly bulged portion 56 of support plate 26. Bulged portion 56 forms an abutment structure for limiting downward movement of plunger 54 to the position shown in FIG. 2. During movement of plunger 54 from its FIG. 1 to its FIG. 2 position the blade portions 38 and 40 are caused to move downwardly alongside of support portion 28 so as to change the direction in which the preset tension in the blade acts. In the FIG. 1 position the blade sections 38 and 40 extend from the left end of the blade in a direction slightly above the central blade section 30; as a result, the tension in sections 38 and 40 causes said sections to have a tendency to press upwardly on plunger 54 and stop member 46. However, as plunger 54 is depressed the tension force in blade sections 38 and 40 is caused to be redirected in a slightly downward direction due to the fact that said sections 38 and 40 change their angle with respect to the direction or plane taken by central blade portion 30. Thus as the plunger 54 moves to its FIG. 2 position the right-hand areas of blade sections 38 and 40 pass below the plane of the corresponding portion of blade section 30 so that the pretension force in sections 38 and 40 acts in a downward direction (instead of in an upward direction as in FIG. 1). As a result, the blade is caused to snap from its FIG. 1 position engaged with contact 46 to its FIG. 2 position engaged with contact 48. Even though the blade has a downward pressure contact with stop member 48 in the FIG. 2 position, yet there is an upward component of force exerted by the tensions in the blade sections 38 and 40 acting against plunger 54. Thus, when the external downward force on plunger 54 is released the blade will automatically snap into engagement with contact 46 as shown in FIG. 3. The control of the blade position is of course effected by movement of plunger 54.

In order to provide the motive force for moving the plunger 54 from its FIG. 1 position to its FIG. 2 position there is provided an impulse mechanism comprising a tubular housing structure 57 fixedly carried on plate section 18. The extreme lower portion of housing structure 57 is internally enlarged to provide a shoulder 60, and the enlarged portion slidably receives a disc member 62. Disc 62 carries a lost motion stem 64 which includes a relatively small diameter lower portion 66, an intermediate enlargement 68, and a relatively large diameter upper section 70.

Slidably positioned in the upper portion of cylindrical housing section 57 is a depressable actuator button 10 having a reduced diameter upper section 67 defining a shoulder 71 for cooperation with an inturned housing flange 72 for limiting the upward slidable movement of the button.

The lower portion of button 10 is hollowed, as at 69, to form a guide structure for slidably receiving the upper section 70 of stem 64, the arrangement being such that stem 64 is accurately guided by structure adjacent both of its ends so as to provide for smooth jam-free operation.

An intermediate portion of housing structure 57 is provided with an annular groove 74 which receives a C-shaped retainer 76. Retainer 76 serves as an abutment structure for a compression spring 78. The other end of compression spring 78 abuts against a thin metal disc 80 which is provided with three downwardly projecting spring fingers 82. The lower end portions of spring fingers 82 are directed inwardly toward the axis of stem 64, and then outwardly at 84 to form cam sections adapted for frictional engagement with the stem enlargement 68. Button 10 constitutes a drive member, stem 64 constitutes a driven member, and spring fingers 82 constitute a releasable drive connection.

In operation, when an external force is applied to actuator 10, either manually or mechanically, the assembly of members 10, 64 and 54 are caused to move downwardly as a unit until the lower face of switch blade 32 abuts against bulged portion 56 of support plate 26. During this downward movement the blade sections 38 and 40 are caused to snap from contact with stop member 46 to stop member 48. Continued application of the downward force on actuator 10 is thereafter effective to cause the outwardly flaring portions 84 of the spring fingers 82 to cam outwardly on stem enlargement 68 so as to snap inwardly onto the smooth surface of stem section 66. The plunger 10 is therefore free to have a downward movement to the FIG. 3 position without resistance from stem 64 or plunger 54. As soon as spring finger sections 84 have passed downwardly beyond enlargement 68 the assembly of members 64 and 54 is free to snap upwardly from the FIG. 2 position to the FIG. 3 position under the influence of the preset tension in blade 32 (provided by deformed portion 42). Thus, the blade is caused to take its FIG. 3 position engaged with stop 46.

It will be seen that during a single depression of actuator 10 the blade 32 is caused to snap from its FIG. 1 position to its FIG. 2 position engaged with stop 48 and back to its FIG. 3 position engaged with stop 46. On release of the downward force on actuator 10 the actuator is propelled upwardly by spring 78 so that spring finger portions 84 snap over the enlargements 68 to the FIG. 1 position. The device is then set for another impulse operation.

The illustrated embodiments employ a casing structure 12 and plunger mechanism 54 which is of conventional construction. As a result the housing structure 57 and its contained components can be easily assembled onto the conventional switch casing structure and utilized to form a complete impulse switch without extensive experimentation, development work or tooling directed especially to the impulse switch structure.

It will be realized that while the drawings necessarily show specific features of construction utilized in one embodiment of the invention, yet the invention is capable of practice in those forms thereof coming within the spirit of the invention as defined in the appended claims.

I claim:

1. In an impulse switch, a housing defining a hollow cavity, opposed spaced first and second electrical contacts in one end of said cavity, an elongated, over-center stressed switch blade in said cavity having one end positioned between said contacts and normally engaging one of said contacts, pivot means in said cavity floatingly supporting a median portion of said blade, a first reciprocable plunger carried by said housing to engage the other end of said blade, abutment means in said cavity limiting movement of said plunger and said other end of said blade, a reciprocable actuator carried by said housing and engageable with said plunger, a second reciprocable plunger carried by said housing for moving said actuator, lost motion means between said second plunger and said actuator, and means biasing said second plunger away from said first plunger.
2. In an impulse switch, a housing defining a hollow switch cavity, opposed spaced first and second contacts in one end of said cavity, an elongated, over-center stressed switch blade in said cavity and having one end extending between said contacts and normally engaging one of said contacts, pivot means in said cavity free-floatingly supporting said switch blade at a median point thereon, a first reciprocable switch actuating plunger carried by said housing and engageable with the other end of said blade, a reciprocable actuator carried exteriorly by said housing for actuating said first plunger, a second reciprocable plunger carried by said housing for moving said actuator, and means biasing said second plunger away from said first plunger.
3. In an impulse switch, a housing defining a hollow switch cavity, first and second opposed spaced contacts in said cavity, an elongated, over-center stressed switch blade in said cavity and having one end positioned between said contacts and urged against the first contact by said stress, a reciprocable switch-actuating plunger carried by said housing and engageable with the other end of said blade, pivot means in said cavity free-floatingly supporting said switch blade between its ends, a reciprocable actuator carried by said housing, said actuator including lost motion means engageable with said plunger, and means carried by said housing and biasing said actuator away from said plunger.
4. In an impulse switch, a housing defining a hollow switch cavity, first and second opposed spaced contacts in said cavity, an elongated over-center stressed switch blade in said cavity and having one end positioned between said contacts and normally biased toward one of the contacts, a contact pivot in said cavity free-floatingly supporting said switch blade between its ends, said pivot contact comprising a plate lying in the bot-

tom of said cavity and having an upwardly extending bowed portion contacting said switch blade,
a reciprocable switch actuating plunger carried by said
housing and engageable with the other end of said
switch blade,
said pivot contact plate including an abutment to limit
movement of said plunger and said blade other end,
a second plunger carried by said housing and engage-
able with said first plunger to actuate the same,
a third plunger carried by said housing and engageable 10
with said second plunger to actuate the same,

and lost motion means between said second and third
plungers.
